UNITED STATES PATENT OFFICE.

ADAM SCHEPPER AND PAUL SCHROEDER, OF BAY CITY, MICHIGAN.

ROLLING RADIATOR SHUTTER.

Application filed March 11, 1925. Serial No. 14,627.

This invention relates to rolling radiator shutters and the like, and particularly to a shutter for use on automobiles for regulating the exposed area of cooling surface and thereby controlling the passage of air through the radiator and automatically regulating the temperature of water therein.

One object of the invention is to provide a very simple, substantial and efficient attachment of pleasing appearance which can be quickly attached to, or removed from the automobile radiator, and which can be operated from the driver's seat in the vehicle.

Another object is to provide a frame which can be stamped from sheet metal, which will be light in weight, and very economical to manufacture.

With the above and other objects in view, the present invention consists in the combination and arrangement of parts, hereinafter more fully described, illustrated in the accompanying drawings, and particularly pointed out in the appended claims, it being understood that changes may be made in the form, size, proportion and minor details of construction, without departing from the spirit, or sacrificing any of the advantages of the invention.

In the drawings:

Fig. 1 is a fragmentary side view of an automobile showing our improved radiator shutter in place thereon.

Fig. 2 is an enlarged fragmentary sectional view of the radiator showing the pipe therein for the passage of the operating cord.

Fig. 3 is an enlarged fragmentary sectional edge view of the lower end of the shutter proper.

Fig. 4 is a front view of the shutter.

Fig. 5 is a sectional plan view taken on the line 5—5 of Fig. 4, the curtain being removed.

Fig. 6 is an edge view illustrating one method of securing the pull chain in position.

Fig. 7 is a front view of the locking plate.

In cold climates where the temperature drops below the freezing point at certain seasons of the year, it is necessary to provide means for regulating the area of the exposed radiator surface to prevent the freezing of the cooling mixture, and when the passage of air is partially or completely cut off, the mixture warms rapidly insuring

the engine operating in the proper manner.

Antifreeze solutions are used to prevent freezing but, unless the area of the radiating surface is reduced, the cooling mixture stays very cold, causing the motor to miss and sputter, with our improved shutter device the exposed radiating surface can be regulated, so that the mixture becomes warm quite quickly, after which the shutter can be lowered if desired.

Referring now to the drawings in which we have shown the preferred embodiment of our invention, the numeral 1 indicates the shutter frame proper, which is usually shaped to conform to the contour of the radiator shell. This frame is provided with a large central opening 2, the edges 3 of the frame being flanged and turned to provide vertically disposed ways or guides 4 in which the edges of the flexible curtain 5 are adapted to travel and which prevent wind getting behind the curtain and blowing and flapping same.

A conventional spring actuated roller 6 is mounted in the lower end of the frame, suitable openings being provided in the side walls thereof to receive the pintle and gudeon of the roller, said lower end being enlarged to house the roller and curtain, thence gradually narrowing to accommodate and guide the curtain proper.

A transversely disposed strip 7 is provided near the lower end of the frame being welded or otherwise secured thereto, the extreme ends 8 being slightly bent to eliminate the possibility of catching and tearing the edges of the curtain, the upper edge of this strip frictionally engages the inner surface of the curtain at all times and serves as a drain for melting snow, rain, etc., which might lodge, or be blown or driven between the curtain and the radiator, the heat of the radiator serving to melt the ice and snow.

The upper ends of the ways or guides are capped by flanging the material thereover to exclude snow, ice and other foreign matter.

A small sheave or pulley 9 is journaled in a bracket 10 riveted or welded to the top section of this frame, and around which a cord 11 is threaded, one end of the cord being secured to the curtain as shown, thence leading up (close to the vehicle radiator 12, and over the sheave 9), thence through an opening in the frame and through a small

pipe section 13 which extends through the radiator core. A chain 14 is then attached to the end of the cord 11 and leads to the instrument board 15 of the vehicle.

5 A conventional locking plate 16 is secured to the instrument board and is provided with an open slot 17 so that the chain may be hooked therein to hold the curtain in any adjusted position, we find that a fabric cord 10 is short lived in this position, and therefore provide a chain as described.

It will of course be obvious that various devices such as reels and the like may be provided for winding the chain to adjust the 15 shutter if desired, but we find the method described to be practical, convenient and economical.

The attachment is secured in place by means of small threaded bolts 18 which extend through the radiator core, a nut 19 being threaded thereon, these can be quickly removed or replaced and the installing or removal of the attachment requires merely a few minutes time.

25 It will also be apparent that the shape of the frame will be varied to suit the different designs and shapes of radiators as the curves, etc., on the different makes of automobiles vary considerable.

30 From the foregoing description it will be obvious that we have perfected a very simple, economical and efficient adjustable radiator shutter for regulating the current of air passing through the radiator.

35 What we claim is:—

1. A rolling radiator shutter for automobiles comprising a sheet metal frame having

an enlarged central opening, the edges of the frame being turned to form guides, the lower ends being curved outwardly and enlarged and having a roller mounted therein and spaced ahead of the automobile radiator, a flexible curtain wound on the roller at the front side thereof, the edges of which curtain travel in said guides, and an inclined drain strip secured to the frame adjacent the curved portion and extending upwardly and forwardly over the roller and frictionally engaging the back of said curtain.

2. The combination with an automobile, of a rolling radiator shutter comprising a sheet metal frame having a central opening, the edges of the frame being turned and bent to form guides, the lower ends being curved outwardly and having a roller mounted therein and spaced ahead of the radiator, a flexible curtain wound on the roller at the front side thereof, the edges of which curtain travel in said guides and the roller being arranged at the rear of the curtain, a drain strip secured to the lower end of the frame and extending upwardly and forwardly over the roller and frictionally engaging the inner surface of the curtain, a sheave journaled to the upper edge of the frame, and an operating cord attached to the curtain and leading around said sheave and to the dash of the automobile for adjusting said curtain.

In testimony whereof we affix our signatures.

ADAM SCHEPPER.
PAUL SCHROEDER.
